PLATE COVER

Hubert E. Christian and David W. Lee, Phoenix, Ariz.,
assignors to Dart Industries Inc., Los Angeles, Calif.

Filed May 21, 1973, Ser. No. 363,241

Term of patent 14 years

Int. Cl. D7—01

U.S. Cl. D7—40

FIG. 1

FIG. 2

FIG. 1

FIG. 2

FIG. 1 is a top plan view of a plate cover embodying our new design;

FIG. 2 is a front elevational view thereof;

FIG. 3 is a bottom plan view thereof; and

FIG. 4 is a vertical cross-sectional view thereof, taken along the line 4—4 in FIG. 1.

We claim:

The ornamental design for a plate cover, substantially as shown.
